US0D1105254S

(12) **United States Design Patent** (10) Patent No.: **US D1,105,254 S**
(45) Date of Patent: ** Dec. 9, 2025

(54) **GAMING MACHINE**(71) Applicant: **AGS LLC**, Las Vegas, NV (US)

(72) Inventors: **Karl Frederick Zedell, Jr.**, Johns Creek, GA (US); **Benjamin Martin**, San Francisco, CA (US); **Carlos Martin Terminel Iberri**, San Jose, CA (US); **Daniel Kendall Harden**, Carmel-by-the-Sea, CA (US); **Zack Stephanchick**, San Francisco, CA (US); **James Ely Tillery**, Tucker, GA (US); **Kevin Hohman**, North Las Vegas, NV (US); **Parry Staley**, Decatur, GA (US); **Matthew Rodgers**, Cumming, GA (US); **Ryan Patrick Rye**, Suwanee, GA (US)

(73) Assignee: **AGS LLC**, Las Vegas, NV (US)(***) Term: **15 Years**(21) Appl. No.: **29/889,960**(22) Filed: **Apr. 18, 2023**(51) LOC (15) Cl. **21-03**
